UNITED STATES PATENT OFFICE.

CARTER J. JOHNSON, OF GREEN BAY, WISCONSIN.

TURNBUCKLE-WRENCH.

1,397,810.

Specification of Letters Patent.

Patented Nov. 22, 1921.

Application filed January 8, 1921. Serial No. 435,812.

To all whom it may concern:

Be it known that I, CARTER J. JOHNSON, a citizen of the United States, residing at Green Bay, in the county of Brown, State 5 of Wisconsin, have invented certain new and useful Improvements in Turnbuckle-Wrenches; and I do hereby declare the following to be a full, clear, and exact description of the invention, such as will enable 10 others skilled in the art to which it appertains to make and use the same.

This invention relates to new and useful improvements in wrenches and particularly to wrenches for turning turnbuckles.

15 One object of the invention is to provide a turnbuckle wrench which when used longitudinally at the side of the turnbuckle, will not rotate on the engaging pin as a pivot.

20 Another object is to provide a wrench of this character which will retain its grip on the turnbuckle when the operator releases his hold thereon.

Another object is to provide a novel means 25 for holding the transverse pin at one end of the wrench from falling out as the wrench is being turned.

A further object is to provide a turnbuckle wrench which has a slidable pin for 30 use in connection with small turnbuckles.

Other objects and advantages will be apparent from the following description when taken in connection with the accompanying drawing.

35 In the drawing:

Figure 1 is a side elevation of a turnbuckle wrench made in accordance with the invention.

Fig. 2 is a top plan view of the wrench, 40 the same being broken away to expose a portion of the interior thereof.

Fig. 3 is a vertical longitudinal central sectional view through the wrench on the line 3-3 of Fig. 2.

45 Fig. 4 is a perspective view showing the wrench when the end pin is used in connection with a turnbuckle.

Fig. 5 is a vertical transverse sectional view through the intermediate portion of 50 the wrench and turnbuckle when the side pin is used.

Fig. 6 is a longitudinal sectional view 55 through the end of the wrench in which the transverse pin is used, together with the turnbuckle, showing the means for retain-

ing the pin in the openings of the legs of the end of the wrench.

Referring particularly to the accompanying drawing, 10 represents a tubular shell formed preferably of metal and having its 60 opposite ends bifurcated to provide the pairs of longitudinally extending legs 11 and 12, the bifurcation at one end of the shell being formed in a vertical plane at right angles to that of the bifurcation at the 65 other end. The legs 12 are perforated as shown at 13, with such perforations in alignment for the reception of a transverse pin 14. In the surrounding wall of the opening in one of the legs 12 there is formed a groove 70 15 in which is seated a coil spring 16, said spring being adapted to snap into the groove 17 in the peripheral face of the end of the pin 14, to prevent the pin from accidentally slipping from the perforations 13 while the 75 wrench is being rotated with the turnbuckle, in the manner shown in Fig. 4. Within the shell 10, inwardly of the legs 11 there is disposed a metal plug 18, said plug being retained in the shell by the transverse pin 80 19, and having the longitudinal central bore 20 in which is fitted the pin 21. The portion of the pin 21 which projects from the end of the shell is disposed centrally between the legs 11, and is adapted to be engaged through the opening of the turnbuckle 22, in the manner shown in Fig. 3, 85 while the legs 11 engage on opposite sides of the turnbuckle. Secured to the inner faces of the legs 11 are bowed springs 23 90 which coöperate with each other to grip the turnbuckle in an embrace sufficient to maintain the wrench on the turnbuckle should the operator release his grasp on the wrench. Formed longitudinally in one side of the 95 inner plug 18' is a complementary plug section 18" in which is formed a longitudinal groove 31 for the reception of the removable transverse pin 14, when said pin is not in use in the legs 12. Secured in this 100 groove 31 is a leaf spring 24 which frictionally engages the pin to maintain the same in the groove. A transverse screw 25 maintains this plug section 18" in the shell.

The plug 18' has a longitudinal pin 105 21' extending longitudinally therethrough which is held by the screw 26. The pin 21' is arranged to be projected into position between the legs 12 upon sliding movement of the section 18'. The pin 21' is of smaller 110

diameter than the pin 21 for the purpose of engagement in the opening of a smaller turnbuckle than can be accommodated by the pin 21. On the screw 26, which projects 5 through a longitudinal slot 27 in the shell 10, there is disposed a coil spring 28, one end bearing against the head of the screw while the other end bears against the washer 28'. This washer is formed for engagement 10 in the notches 10' in the shell at opposite sides of the slot, to hold the screw and section 18' in its different slidable adjustments.

The inner end of the plug 18' is cut off obliquely, as is the inner end of the section 15 18'' to form a recess 29 to receive the reduced end of the section 18. When the pin 21' is to be projected for use between the legs 12, the screw 26 is grasped and moved longitudinally in the slot 27 so that the section 20 18' will be moved and its obliquely cut end will move from one face of the reduced end of the section 18. By loosening the screw 26 the pin 21' can be projected through the section 18' to a greater or lesser 25 distance, so that the pin will project beyond the outer ends of the legs 12, thus enabling the operator to use the pin on turnbuckles which are in inconveniently reached places.

30 When the transverse pin 19, which is disposed through the shell and the inner plug section 18, is passed through the central opening of the turnbuckle, the adjacent side of the turnbuckle will lie in a longitudinal 35 groove 30, formed in the side of the shell, thereby preventing the body of the turnbuckle from rotating on the pin as its axis. Thus the turnbuckle and wrench body can be properly grasped and held while the 40 wrench is rotated with the turnbuckle, in a direction above the longitudinal axis of the turnbuckle.

Thus the wrench is capable of a number of different uses in connection with a turnbuckle, as well as being capable of use with 45 turnbuckles of different sizes.

The exterior of the shell of the wrench is knurled or scored to insure a firm grip by the hand of the operator.

50 What is claimed is:

1. A turnbuckle wrench including a shell having a bifurcation at each end, each bifurcation being formed in a plane at right

angles to the other, the legs of the bifurcation at one end of the shell being formed 55 with alining perforations, a removable pin disposed in said perforations, and a resilient means carried by one leg of the last-named bifurcation for holding the said pin against accidental displacement from the perforations.

2. A turnbuckle wrench including a shell having its opposite ends bifurcated with resultant pairs of longitudinally extending legs, a stationary plug in one end of the shell, a second plug movable longitudinally within the other end of the shell, a pin carried by the stationary plug axially of the shell and lying with turnbuckle engaging end between the legs of the corresponding 60 end of the shell and a pin carried by the movable plug and projecting therefrom and movable therewith into and out of position to lie with one end between the legs of the corresponding end of the shell.

3. A turnbuckle wrench comprising a shell having an end bifurcated with resultant spaced legs, said legs having alining perforations, a pin removably engaged in the perforations, a plug slidably mounted 80 in the same end of the shell, and a pin carried by the plug and movable therewith into and out of position to lie between the perforated legs of the shell.

4. A turnbuckle wrench comprising a 85 shell having its ends bifurcated with resultant pairs of spaced legs and having a longitudinal turnbuckle receiving groove in its outer face, a plug within one end of the shell, a securing pin passed through the 90 shell and plug and projecting from the shell through the longitudinal groove to engage a turnbuckle, a second pin carried by the plug and lying with one end between the corresponding legs of the shell and a 95 second plug slidably mounted in the other end of the shell and having a pin movable therewith into and out of position to lie between the legs at that end of the shell.

In testimony whereof, I affix my signature, in the presence of two witnesses.

CARTER J. JOHNSON.
